UNITED STATES PATENT OFFICE.

OTTO KATTENHORN, OF BATTLE MOUNTAIN, NEVADA.

AIRSHIP-PROPELLER.

1,001,043.

Specification of Letters Patent. Patented Aug. 22, 1911.

Application filed December 15, 1898. Serial No. 533,155.

To all whom it may concern:

Be it known that I, OTTO KATTENHORN, a citizen of the United States, residing at Battle Mountain, in the county of Lander and State of Nevada, have invented certain new and useful Improvements in Airship-Propellers, of which the following is a specification.

This invention relates to air ships, and 10 more particularly to means for propelling the same, and has for its object to provide a means for controlling the transverse contour of the under surface of pivoted wings operating on the same principle as the wings 15 of birds.

Another object of the invention is to provide a means for flexing, or bending a vane of the kind mentioned to present a concave surface in the direction of its movement 20 during each stroke.

An important object is to provide a means for governing the relative movement between the different parts of the wing longitudinally thereof, so that at the time of a 25 stroke the surface of the wings will be inclined longitudinally in such a direction as to give a forward impulse both on the upward and downward stroke of the wings, as well as to give a lifting impulse on each 30 downward stroke.

Another object of the invention is the provision of a novel means for giving pivotal movement to a wing.

Another object is to provide a novel form 35 of operating mechanism for inducing different degrees of movement in different portions of a wing laterally thereof.

Other objects and advantages will be apparent from the following description, and 40 it will be understood that changes in the specific structure shown and described may be made within the scope of the claims without departing from the spirit of the invention.

45 In the drawings forming a portion of this specification, and in which like numerals of reference indicate similar parts in the several views, Figure 1 is a top plan view of a skeleton frame of an air ship equipped with the present invention, Fig. 2 is a front view thereof, Fig. 3 is a side view, Fig. 4 is a detail front view of one wing and the operating connections therefor, with the device on a downward stroke, Fig. 5 is a similar 50 view showing the device on the upward stroke, Fig. 6 is an end view of the driving

shaft, Fig. 7 is a perspective view of one end of the crank shaft, Fig. 8 is a detail sectional view of the mounting for the wings and operating cross arms, Fig. 9 is a fragmentary view of a propelling mechanism in which the driving means is modified.

Referring to the drawings, there is shown a frame A comprising the longitudinally extending side beams 10, which are tapered 65 at their opposite extremities as shown at 11, and carry the "blade-like" cross pieces 12 connected between their ends. Transverse beams 13 are carried between the members 10, upon which is suitably journaled the 70 drive shaft 13'. A suitable motor of any type as indicated at C may be mounted upon the frame, and connections made between this and the shaft 13'. Secured to the outer sides of the members 10, there are longitudinally 75 spaced brackets 15, each comprising an approximately U-shaped body portion, having the extremities of its opposite arms extended laterally as at 16 to provide securing portions, which may be suitably perforated for 80 the engagement therethrough of fastenings as shown. The flanges are extended longitudinally of the beams 10.

Carried between the arms of the member 15, there is a central shaft 17, upon which there are pivoted independently the cross arms 20 and 21. Carried upon the central portion of the member 15, and extending outwardly therefrom, there is a suitable ball member 17' upon which there is carried a 85 socket member 18 supporting one inner corner of a wing B. The wing B comprises a rectangular framework including the lateral arms 19 which are gradually tapered toward their outer ends, and the longitudinal struts 22 coengaged between their opposite extremities. The lateral members 19 are of flexible material and connected to their extremities and extending from opposite sides, there are cable members 23 connected to the extremities of the cross arms 21 at the adjacent sides of the frame, the upper cable being extended downwardly through the body of the machine, and the lower one being extended upwardly, each being connected to the respective ends of the cross arm 21 at the opposite side of the machine, from which point they are carried to the extremities of the adjacent lateral arms 19' and secured as shown. The cables thus intersect each other centrally of the frame, and hold the opposite wings rigidly 95 100 105 110

in their relative positions with respect to the horizontal and making their movement synchronous in a common direction.

Secured intermediately to the opposite sides of the lateral members 19, there are cables 24 extending inwardly and being secured to the respective extremities of the cross arms 20, and being carried parallel to the first mentioned cables and connected 10 similarly to the arms 20' upon the opposite side of the frame, from whence they are extended to the intermediate portions of the lateral members 19'.

It will be noted that the shaft 13' is provided with crank portions 25 and 26 disposed respectively in the plane of the cables 23 and 24. There is one of these sets of cranks at each end of the shaft, and it will be noted that the crank portion 25 is arranged to move in a wider radius than the crank 26 which is spaced from the radius of the crank 26 a distance of approximately thirty degrees. The forward set of cranks is advanced sixty degrees beyond the rear set with respect to the axis of the shaft, and the direction of movement thereof. Thus in operation, when the shaft 13' is rotated in a direction indicated by the arrow in Fig. 2, the crank portions 25 connected to the cables 23 moving in a greater arc give a greater degree of movement to the end portions of the wings, than the intermediate portions thereof, and the crank portions 26 connected to the cables 24 being spaced inwardly of the cranks 25, and rearwardly thereof, the movement of the intermediate portions of the vane is retarded at the end of each stroke and also at the beginning of the stroke, and the wings are flexed or bent so that they are always concaved in the direction of their movement. The rearward set of cranks being set at an angle of approximately sixty degrees to the forward set with respect to the axis of the shaft their operation of the rear portions of the vane occurs somewhat later than the movement of the forward ends, so that on the downward stroke the outer portions of the wings will be inclined downwardly from the rear toward the front, and on the upward stroke will be inclined upwardly from the rear toward the front of the machine. A forward impulse is thus given to the machine, and by reason of the concavity of the surfaces presented against the air during the stroke of the wings, the maximum efficiency is derived from the operation of the device.

It should be observed that by the form of connections provided but one shaft need be used on small machines but in Fig. 9 there is illustrated a modified form of the device in which two shafts are utilized, which may be found desirable in machines of large size, and in addition there is illustrated an intermediate crank portion F connected to a cen-

tral set of cross pieces and lateral members similar to those at the forward and rear ends of the wings. It will be noted that the intermediate set of cranks are spaced intermediately of the forward and rear sets with respect to the periphery of the crank shaft, so that the longitudinal inclination of the wings will be properly sustained.

It will be apparent from the foregoing that the number of lateral members and crank operating portions may be multiplied as much as desirable, and the spacing of the cranks radially of the shaft and peripherally thereof may be varied as found desirable. It will be also understood that any desirable construction of frame may be utilized for the support of the device to adapt the device for use upon various types of machines.

What is claimed is:

1. A device of the class described comprising a central body portion, laterally extending flexible wing members carried thereby, a plurality of independently pivoted cross arms disposed transversely with relation to the plane of the wings, cables secured to the outer portions of the wings and extending from opposite sides thereof to the extremities of certain of the cross arms, cables connected to the intermediate portions of the wings and extending over certain other of the cross arms, and operative means engaged with the cables for different relative movement thereof for oscillation of the wings and flexing thereof to present a concave surface in the direction of their movement.

2. A device of the class described including an operating shaft having radially and angularly spaced crank portions, a pivoted flexible wing, and operating connections between the outer and intermediate portions of the wing and respective crank portions of the shaft.

3. A device of the class described including a driving shaft having crank portions radially and angularly spaced thereon, a pivoted flexible wing and operative connections between the outer portions of the wing and respective crank portions of the shaft, for oscillation and coincident flexing of the wings.

4. A device of the class described including a driving shaft, angularly spaced crank portions formed thereon, a pivoted flexible wing, and connections between the outer portion of the wing and the intermediate portion of the wing and respective crank portions of the shaft.

5. A device of the class described comprising a support portion, a pivoted flexible wing carried thereby, a driving shaft carried by the support portion, longitudinally spaced cranks carried by the shaft, certain of said cranks being spaced radially and angularly with respect to the axis of said shaft, said

cranks being disposed in different radii of the axis of the shaft, operative connections between certain of the cranks and the extremities of the wing, and operative connections between the remaining cranks and the intermediate portion of the wing, the cranks engaged with the forward end of the wing being advanced in their orbit beyond those engaged with the rear end of the wing, for 10 the purpose described.

6. A mechanism for oscillating and flexing a wing comprising a shaft, radially and angularly spaced crank portions formed thereon, independently pivoted cross arms, 15 a pivoted flexible supporting member, con-

nections between the extremity of the web-supporting member and the opposite extremity of one of the cross arms and with certain of said crank portions, and connections between the intermediate portion of 20 the web-supporting member and the other of said cross arms and the remaining crank portions.

In testimony whereof I affix my signature, in presence of two witnesses.

OTTO KATTENHORN.
